HAIR CURLING DEVICE

John H. Wilburn, Jr., Texarkana, Tex.

Application July 3, 1935, Serial No. 29,692

3 Claims. (Cl. 132—37)

This invention relates to a hair curling device and more particularly to an instrumentality for use in rolling human hair into what are termed finger curls.

The principal object of the present invention is to construct an apparatus which clasps and holds the hair until the curl is completed and to eliminate the use of heated curling irons.

Heretofore, beauticians have formed so-called finger curls by moistening the hair and winding it around an ordinary led pencil but this procedure is very awkward and slow and often necessitates a considerable amount of work on the part of the operator as the wet hair clings to the wood and many times destroys the curl when the pencil is removed. This method also entails the holding of the ends of the hair with the fingers and thumb while the pencil is turned to form the curl.

By using the present curler, even the most unskilled operator can form perfect curls as the prongs of the device are smooth wire rods and are easily removed from the curl. After the curl has been formed, conventional hair pins may be placed in the hair to hold the curl and retain it in proper conformation during the time it is drying from the lotion which is customarily used to saturate the hair before the curl is formed.

In the drawing:

Fig. 1 is a side elevation of the movable wire rod which forms the upper prong of the device.

Fig. 2 is a side elevation of the handle element in which the openings and indentations are shown in cross sectional lines.

Figs. 3 and 4 illustrate a side and top elevation respectively of the spring member which holds the upper lever and prong in contact with the handle member.

Fig. 5 is a side view of the assembled device showing it in dotted lines when in open position.

Fig. 6 is a top plan view of the assembled curler.

Fig. 7 is a vertical section through the handle member taken on line 2—2 of Fig. 6.

More particularly in the drawing:

Numeral 1 denotes a horizontal round rod made of wire which is bent upwardly at 2 and downwardly at 3. This rod forms the upper movable lever of the hair curler and is retained in handle member 4. This handle member may be composed of wood or molded nonheat conducting material such as bakelite. The upper surface of the member 4 is centrally slotted at 5. The forward portion of the slot is rounded at 6 to form a pivot point. A vertical bore 7 is formed at the rearward portion of the slot and, as shown in

Fig. 2, the central portion of the handle is cut away so that the slot 5 tapers rearwardly from the nose 6 toward the opening 7.

The rear portion of the member 4 is thickened so as to be readily grasped in the operator's hand while the forward portion of the handle beyond the nose or pivot point 6 is cut away to form a transverse groove 17 having a forward lug or nose 8. A longitudinal bore or socket 9 is made in the front end of the handle to accommodate a straight rod member 10 which forms the lower holding means for the curl.

Near the forward end of the handle and approximately at the forward end of the slot 5 is a shallow transverse groove 11 while adjacent 15 the middle of the handle is a second deep transverse channel 12.

A rod 13 is bent into a substantial parallelogram with overlapping ends 15 and 16 to form a spring 14 and, as shown in Fig. 3, the overlapping 20 ends are bent outwardly from one another to thus form a compression member.

Referring to Figs. 5 and 7 of the drawing, it will be noted that after the lower rod 10 has been affixed in its socket the upper bent lever rod 1 25 is placed in the groove 5 between the prongs 8 with the depending portion 3 of the rod lying in the bore 7. The spring 14 is thereafter positioned so that the free end 15 lying in the transverse groove 11 and, as shown, the straight side 30 opposite the free ends fits in the deep channel 12. It will be readily understood that a simple rubber band may be looped in the upper and lower grooves in lieu of the compression spring. This is of value in the event that the spring breaks 35 and a replacement is not available.

In operation the hair curler is grasped in the hand of the operator who presses the section 2 of the rod 1 which causes the rod to pivot over the nose 6 against the tension of the assembly 40 spring 14. The downwardly bent section 3 of the rod descends through the opening in the handle as shown in dotted lines in Fig. 5.

The hair to be curled, which has previously been saturated with some lotion, is grasped at the ends and placed between the opened rods 1 and 10, whereupon the resiliency of the spring clamps the hair tightly and the operator then rotates the handle member 4 causing the strands of hair to be wound up or curled around the rods. Hair pins or other fastening devices can then be placed in the curl and the rods 1 and 10 slipped from the curl.

The device is rugged in construction, econom- 55

ically manufactured and easily dissembled for replacement of damaged parts.

What I claim is new and useful is:

- 5 1. A hair curler including a solid handle portion having an extended rod rigidly affixed in one end thereof, an extended pivoted rod normally lying in a groove formed in the upper face of said handle, a resilient coupling embracing said handle and binding on said pivoted rod to normally retain said rods in contact with one another.
- 10 2. A hair curler including a heat insulated handle, said handle being provided with a longitudinal groove in its upper edge, one end of said groove terminating in a transversely formed V-shaped slot, a vertical opening in said handle near its center and extended pivotally mounted rod so bent as to normally lie in the said longitudinal groove and bisect said V-shaped slot, the said rod being downturned adjacent its opposite end and terminating in said vertical opening; a second extended rod fixedly secured in a socket in one end of said handle and lying in horizontal

relation to said bent rod, and a spring member overlying the said bent rod and retained in said transverse slot, said spring normally urging the said pivoted rod into engagement with said fixed rod.

- 15 3. In a hair curling device of the character described, a heat insulating handle, said handle having a longitudinal slot formed in a portion of its upper surface extending inwardly from one end thereof, a bore formed in the slotted end of 1 said handle adjacent the lower portion of said slot, an extended metal rod retained in said bore, a second metal rod lying in contact with said longitudinal slot in said handle, said second mentioned rod normally abutting the said first mentioned rod, the opposite end of said second rod being bent upwardly away from said slot and having its end portion depending into a vertical opening in central portion of said handle, a resilient member attached to said handle and binding 2 on said rod to hold the same in horizontal contact with said first rod.
